UNITED STATES PATENT OFFICE.

MILTON F. WILLIAMS, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

DUMPING-CAGE FOR CRUSHERS AND PULVERIZERS.

No. 836,161.

Specification of Letters Patent.

Patented Nov. 20, 1906.

Application filed July 24, 1905. Serial No. 271,018.

To all whom it may concern:

Be it known that I, MILTON F. WILLIAMS, a citizen of the United States, residing at St. Louis, Missouri, have invented a certain new and useful Improvement in Dumping-Cages for Crushers and Pulverizers, of which the following is a full, clear, and exact description, such as will enable others skilled in the art to which it appertains to make and use the same, reference being had to the accompanying drawings, forming part of this specification, in which—

Figure 1 is a vertical sectional view through my improved machine. Fig. 2 is a sectional view on the line 2 2 of Fig. 1, and Fig. 3 is a detail view of a portion of the cage or grinding-surface.

This invention relates to a new and useful improvement in dumping-cages for crushers and pulverizers, the object being to construct a cage in such manner that when the machine chokes is it possible to dump the contents thereof without raising the cover and removing the material from the top.

In the operation of my machine, especially where electric motors are employed as a driving medium, it sometimes happens that the fuse will blow out or other accidents happen during the time that the machine is in operation, causing the machine to stop and leaving the material being operated upon in the machine. Under these circumstances it is impossible to start the machine without first removing such material, it being necessary to get the machine up to full speed before introducing the material thereinto to be reduced.

My present invention therefore consists in making the grinding-surface or cage, with which the revolving beaters coöperate to reduce the material, wholly or partly movable, means for moving the same extending to the exterior of the machine, whereby in the event that the machine stops with a load or becomes choked it is possible for the operator to dump the contents of the cage and free the machine.

In the drawings, 1 indicates the side plates of the casing, and 2 is the cover. 3 indicates the breaker-plate, arranged at the front end of the machine and on which the material is first operated upon by the revolving hammers or beaters 4, which are pivotally

mounted in the hammer-supports 5, arranged on a transversely-disposed shaft 6. 7 55 indicates a cage or grinding-surface which coöperates with the revolving hammers or beaters 4, the side supporting-bars of which are pivotally mounted at 8 at the rear end of the machine, so that said cage or grinding- 60 surface can swing down to the position shown in dotted lines in Fig. 1. The free end of the cage is provided with devices 9, which extend upwardly through openings formed in offsets in the side walls of the casing, said 65 upwardly-extending devices being preferably continuations of a cross supporting-rod 10, passing through the side bars of the cage. The upper ends of these devices 9 are provided with openings 11, with which coöper- 70 ate wedge-keys 12, that rest on horizontally-disposed portions of said offsets. A wire rope, chain, or cable 13 is also connected to the devices 9.

In operating position the cage or grinding- 75 surface is held in place by the wedge-keys 12, which pass through the upwardly-projecting devices 9 and rest upon the offsets in the side walls of the casing, and by driving these wedge-keys inwardly the free end of the cage 80 may be adjusted to take up wear of the ends of the revolving hammers or beaters. In the event that it is desired to dump the contents of the machine the wedge-keys 12 are driven out of the devices 9 and the operator 85 holding the rope or cable 13 permits the cage to swing down to the position shown in dotted lines in Fig. 1, in which position the contents of the machine will be discharged.

To restore the cage to normal position, the 90 ropes or cables 13 are operated to raise the free end of the cage until the devices 9 project up through their registering openings in the offsets in the side walls of the casing, at which time the wedge-keys may be driven 95 through the openings 11 to hold the cage in position.

Having thus described the invention, what is claimed as new, and desired to be secured by Letters Patent, is—

1. In a machine of the character described, the combination of a casing, revolving hammers or beaters, a pivoted cage or grinding-surface, upwardly-extending devices on the free ends of said cage or grinding-surface 105 which pass upwardly through openings in

the casing, and means coöperating with said upwardly-extending devices for locking the cage in normal operating position; substantially as described.

- 5 2. In a machine of the character described, the combination of a casing, revolving hammers or beaters, a pivoted cage or grinding-surface, upwardly-extending devices on the free ends of said cage or grinding-surface which pass through openings in the casing, and adjustable means coöperating with said upwardly-extending devices for adjustably holding the free end of said cage in operating position; substantially as described.
- 10 3. In a machine of the character described, the combination of a casing having lateral offsets in its side walls, revolving hammers or beaters, a pivotally-mounted cage or grinding-surface having upwardly-extending

devices passing through openings in the lateral offsets in the side walls of the casing, means coöperating with said upwardly-extending devices and resting on horizontal portions of said offsets for adjustably supporting the cage in normal operating position, and chains or cables connected to said upwardly-extending devices whereby said cage may be swung on its pivot to dump the contents of the machine and restore it to normal position; substantially as described.

25 30 In testimony whereof I hereunto affix my signature, in the presence of two witnesses, this 14th day of July, 1905.

MILTON F. WILLIAMS.
